ANTIGLARE DEVICE

Bernard Waldman, Springfield, Mass.

Application April 1, 1947, Serial No. 738,688

1 Claim. (Cl. 2-14)

1 This invention relates to improvements in anti-glare devices.

The principal objects of the invention are directed to the provision of an anti-glare device which is adapted to be worn by the operator of a vehicle and is so constructed and arranged as to shield the left eye of the operator against the glare of the lights of an oncoming vehicle.

As a special feature of the device of the invention, the device is made from transparent material which may be colored as desired and it is so shaped that as it is supported by a band on the head of the wearer a side portion is disposed at the left temple and at the outer side of the left eye with a lateral forward portion which partly overlies the left eye.

In this position the operator has clear vision straight ahead but to avoid the glare of oncoming headlights the wearer merely tilts the head sideways to bring the lateral portion in line with the glare.

With the foregoing and various other novel features and advantages and other objects of my invention as will become more apparent as the description proceeds, the invention consists in certain novel features of construction and in the combination and arrangement of parts as will be hereinafter more particularly pointed out in the claim hereunto annexed and more fully described and referred to in connection with the accompanying drawings wherein:

Figs. 1 and 2 are side and front elevational views of the anti-glare device embodying the novel features of my invention;

Fig. 3 is a sectional elevational view on the line 3-3 of Fig. 1; and

Figs. 4 and 5 are front and side elevational views of the device as it is worn by a person.

Referring now to the drawings more in detail, the invention will be fully described.

The anti-glare device includes in a broad way a shield 2 and a head band 4.

The shield 2 is formed to have a side member 6 which is generally tapering rearwardly from the forward side thereof. From the forward end of the side member a lateral eye portion 8 extends inwardly and at an angle relative thereto. Such angle will be in the neighborhood of ninety degrees or more.

The members 6 and 8 will preferably be integral and formed from pliable material such as plastic. The material will be transparent and tinted as, for instance, green so as to be capable of shutting out appreciable amounts of glare from headlights.

2 A reinforcing frame or binding construction is provided which consists of upper and lower channel members 10 and 12 which receive and are secured to upper and lower marginal edges of the member 6. The channels may be secured to the member 6 by adhesive crimping or the like and may be made from thin metal.

The head band 4 preferably consists of a strip of resilient material which may be thin metal, plastic or any material adapted to yieldingly grip the head of the wearer when formed into the shape of a semi-circle as shown. The head band may be adjustable in the manner well known in the art.

One end of the band 4 is pivoted to the rear end of the member 2 by any suitable means such as a rivet 14 or the like.

The device is adapted to be worn by an operator of a vehicle by placing the head band on the head. The member 2 is swung on the band so that the member 6 is disposed adjacent the left temple and the lateral member 8 is disposed forwardly of the left eye all as shown in Figs. 4 and 5.

With the device so located, the left eye is partly shielded by the lateral member 8, from the glare of oncoming lights while at the same time the operator may see through the member 8 since it is transparent.

The operator, by tilting the head, may completely cover the eye so as to be shielded from glaring headlights.

The invention may be embodied in other specific forms without departing from the essential characteristics thereof. Hence, the present embodiments are therefore to be considered in all respects merely as being illustrative and not as being restrictive, the scope of the invention being indicated by the appended claim rather than by the foregoing description, and all modifications and variations as fall within the meaning and purview and range of equivalency of the appended claim are therefore intended to be embraced therein.

What it is desired to claim and secure by Letters Patent of the United States is:

An anti-glare device adapted for shielding one eye only of the wearer comprising in combination, a head-band made from an elongated strip of a resilient material formed semi-circularly to extend upwardly at a side of the head of the wearer and inwardly and over the crown thereof adapted to yieldingly embrace the head, a shield formed from relatively thin and colored material to have integral side and forward eye portions

disposed in relatively angular planes, said side portion having a relatively narrow rear end and upper and lower relatively diverging marginal edges extending forwardly from said rear end to a relatively wider forward end, a pivotal connection between said rear end of the side portion and an end of said band, said forward portion of the shield extending inwardly from the forward end of the side portion having an inner substantially vertical edge and having a width 10 substantially equal to that of the outer end of the side portion, all adapted and arranged whereby with the head-band embracing the head of a wearer the side portion of the shield overlies a side of the head and extends forwardly 15 towards the eye adjacent thereto and the forward eye portion is disposed in front of said eye while said shield may be swung up or down to adjust said forward eye portion relative to said eye.
